METHOD AND MACHINE FOR SEWING
SAHARA SANDALS

Charles Martin Bagshaw, Leicester, England, assignor to United Shoe Machinery Corporation, Paterson, N. J., a corporation of New Jersey

Application December 31, 1934, Serial No. 759,899
In Great Britain January 6, 1934

5 Claims. (Cl. 112—34)

The present invention is concerned with improvements in or relating to shoe making or sewing, and has particular reference to a novel manner of, and means for, forming a seam between two shoe parts, especially between a shoe upper and a sole of the type, used for so-called Sahara sandals, which has an upturned marginal portion to which the upper is connected.

The form of Sahara sandal now commonly used comprises a sole moulded to have its margin turned up all round and having its upper laced, by a hand operation, with a thong or cord to this margin. The hand lacing operation just referred to has been, however, a very slow one (even a skilled work person generally requiring to spend about as long as twenty minutes in lacing one sandal) and has added considerably to the labour cost involved in making the sandals, which have commonly to be put upon the market at a very low price. It is one of the various objects of the present invention to provide an improved method of securing together the upper and sole of a Sahara sandal which will produce a sandal having advantages of, and presenting a somewhat similar appearance to, a sandal that has been hand laced while, nevertheless, capable of being performed by mechanical aid more rapidly than hand lacing can be carried out.

I have found that it is possible to employ a shoe sewing machine of the well-known chain-stitch McKay type, preferably modified in certain respects hereinafter mentioned, to form the union between upper and sole. In carrying out this method, an upper and sole may be employed prepared exactly as would be the case for hand lacing, the upper being conveniently, as is frequently done in the case of hand laced sandals, formed in at least two separate portions (a heel part portion and a forepart portion) which are perforated along their margins to receive the fastening means (which will ordinarily be a thick thread or cord) and the sole merely having an upstanding rim (with no out-turned flange or the like thereon) conveniently perforated and it may be bevelled along its upper margin, and the upper and sole are conveniently presented to the sewing machine merely in the loose state and not previously attached together in any fashion. The sewing machine is preferably equipped with driving means including a one revolution clutch so that upon actuating a treadle the operator can cause the machine to sew a single stitch. The operator will place the upper and sole in assembled relation upon the usual horn of the machine (hav-

ing both hands free for this purpose) and will sew a succession of single stitches positioning the work upon the horn so that the needle alternately enters the sole margin and the upper margin. If the sole and/or upper be perforated, as above indicated, the operator will position the work prior to each stitch forming reciprocation of the needle so that the needle (which stops in raised position) will descend through a perforation therebeneath. The feeding mechanism with which ordinary McKay sewing machines are provided which is operative to feed the work from right to left of the machine (looking at the machine from the front) is conveniently rendered inoperative and I have found that quite satisfactory and not unreasonably slow sewing may be obtained when the operator manually takes care of the feed of the work in the special manner above indicated—viz, so that at one stroke, the needle will enter the sole margin while, at the next stroke, it will enter the upper margin, and so on.

By way of example the accompanying drawings show one form of sandal, the upper and sole of which have been joined together by a method in accordance with the invention.

In the drawings:

Figure 1 is a perspective view of the illustrative sandal (before it has had its heel attached thereto) only a portion of the novel seam between upper and sole being shown in full, but it being understood that the seam is actually continued in similar fashion to that shown round both the toe and heel portions of the sandal; Figure 2 is a fragmentary view to a larger scale than Figure 1 illustrating clearly the nature of the seam between upper and sole; Figure 3 is a detail view of certain parts of the McKay sewing machine which is preferably used in sewing the seam; Figure 4 is a detail view of the new thread finger; Figure 5 is a detail view of the presser-foot; and Figure 6 is a view in front elevation of the head of the complete machine.

The illustrative sandal comprises a sole moulded to have an upstanding marginal portion 3. The upper is formed of two separated portions, a heel part portion 5 and a fore part portion which, in the example illustrated, is itself actually composed of two parts 1 and 9. Prior to the assembly of upper and sole together, the lower marginal portion of the former is provided with a series of equally spaced perforations 11 therearound, while the marginal portion 3 of the sole is perforated with a series of correspondingly spaced perforations 13. As

seen in the drawings, the upper and sole margin are connected together by a seam 15 which, besides serving to join these elements, has an attractive decorative appearance somewhat allied to that resulting from hand lacing, as previously performed.

The seam 15 in the shoe shown in the drawings is produced in a well-known McKay type sewing machine of the general nature of that illustrated and described in the patent to Richardson No. 1,412,423, dated April 11, 1922. To use the machine for forming the seam shown in the drawings, the needle and cast-off are conveniently retained unaltered, but the feed point is removed and its actuating mechanism is utilized to operate a new thread finger which I have found it desirable to provide. A change also has been made in the shape of the presser foot. As already mentioned, the machine is preferably provided with a one-revolution clutch of any well-known construction whereby, upon depression of a treadle, the needle is caused to move once downwardly from a fixed upward stopping position and then upwardly once again to the stopping position to form a single stitch. I have found it preferable also to lock the horn in a fixed position in which the curved portion of the horn extends directly to the right of the sewing position.

30 The modified presser foot indicated at 18 in Figures 3 and 5 with which the machine is equipped has a horizontal work-engaging portion about $\frac{1}{2}$ inch in length which extends to the right from a locality some $\frac{1}{16}$ inch or less 35 to the right of the axis of the needle. This portion is conveniently about $\frac{3}{8}$ inch in width and may be slotted so that it forms a fork having two parallel arms extending towards the needle.

40 It has already been mentioned that the machine is provided with a one-revolution clutch. This clutch is so arranged that the machine is always stopped when the needle is near the highest point of its stroke. The presser foot lift is 45 so timed that the presser foot will be raised from the work at the stopping position, so that at the stopping position the operator is free to position the work for the next stitch.

In the ordinary machine, the arm 19 carries 50 the feed point which feeds the work intermittently during the formation of the seam. In the present machine the feed point is done away with, and the arm 19 is utilized to carry the new thread finger above referred to. This thread finger is formed as a small spade-shaped member 21, the plane of which is horizontal and which has at its left hand side an edge some $\frac{1}{16}$ inch in length. This member is normally located at the right of the axis of the needle, 55 but is arranged to have a movement across the axis of the needle and underneath the needle. When, during the production of a seam like that shown in the drawings, the needle is in stopping position, it will, as already mentioned, be near 60 the upper limit of its stroke and will have a loop of thread coming up from the work passing around its barb. The presser foot will be raised and the operator will position the work (by 65 moving it transversely of what would be the line of feed in an ordinary machine) for the next stitch. Having done this, he will depress the treadle to cause the machine to turn through one revolution and the next stitch will be formed, but I have found that, owing to the sidewise 70 displacement of the point at which the needle

is to enter the work and the point from which comes the loop of thread which passes round the needle, there is some tendency for the needle in its descending stroke to lose the said loop of thread which would, of course, result in a dropped stitch. It is to avoid this tendency that I provide the thread finger above mentioned. This is given such a motion that just as the needle begins to descend it (the thread finger) passes from right to left across the axis of the needle 10 and just below the point of the needle. Its said left hand edge contacts with both legs of the loop of thread passing round the barb of the needle and urges them to the left. The thread finger then begins to retract and just 15 passes to the right of the axis of the needle as the needle begins to descend so that the parts just clear each other. The described action will, however, have been effective to ensure that the loop of thread in the barb of the needle is not 20 in such position as the needle descends that the needle will lose it in its descent.

As has been stated, the needle enters the work at points successively staggered with relation to each other. In order that the work may be 25 positioned correctly under the needle, without unduly stretching the loop of thread on the needle, the one-revolution clutch with which the machine is provided is arranged to stop the machine after the needle has moved downwardly 30 a short distance from its highest position so that the loop of thread on the needle is slackened to permit the work to be easily moved transversely of what would be, in an ordinary machine, the line of feed.

To impart the desired motion to the thread finger it is rigidly secured to the lower end of a block 23, the upper end of which is pivotally mounted on the arm 19, which arm is actuated as in the machine of the patent above referred 40 to, through a link 25 and lever 27 from a cam 31 on the cam shaft of the machine. The thread finger is yieldingly held in position by a spring 33 stretched between the lower end of the block 23 and the link 25. The movement of the block 45 23 under the influence of the spring is limited by the stop pin 35 on the arm 19.

This arrangement is such that the motion of the thread finger in the direction of right to left (that is, its motion from its normal retracted position towards and across the axis of the needle) is a yielding one so that, should the machine be so wrongly adjusted that the thread finger in moving from right to left actually contacts with the needle, breakage of the needle or 55 thread finger is not so likely to occur as it would be if the motion of the thread finger was positive in this direction.

The operation of the machine to sew a seam 15 for a sandal such as that shown in the drawings will have become clear from the foregoing, but it may be convenient briefly to recapitulate it at this stage.

It will be convenient for the operator to begin by sewing together the sole and the heel portion 65 5 of the upper. The operator (who will have both hands free for this purpose) will place the two parts together in proper register and bring the two parts over the horn of the machine, the plane of the sole being more or less vertical and the 70 horn tip contacting with the marginal portion 3 at the interior surface thereof. The operator will depress the treadle whereupon the needle will descend through the perforation into the horn tip wherein it will have the thread looped 75

round it by the whirl and will then be retracted, the presser foot holding the work down while the needle draws the loop of thread upwardly through it. Just as the needle reaches the highest point of its stroke, the presser foot is raised and after the needle has started on its down stroke the machine stops. Let it be supposed that the first perforation penetrated by the needle is a perforation 13 in the sole. The operator is then able rapidly to position the work so that the perforation 11 (in the upper part) which is next adjacent to the perforation 13 through which a stitch has been formed directly underlies the needle and when once this is done 15 presses the treadle again, whereupon a stitch is formed through the perforation 11. In this fashion the operator will sew alternate stitches through the sole and upper, producing the seam 15 illustrated in the drawings. When the heel 20 part portion 5 of the upper has been sewn all round its lower periphery to the sole, a decorative effect may be obtained along that marginal portion of the sole at which, in the sandal shown in the drawings, there is a gap between the parts 25 of the upper, by alternatively making the needle of the machine pass through the perforations 13 in the sole margin and pass just clear of the edges of the sole. This produces the ornamental seam seen at 17 of the drawings. The fore part 30 portions 9 and 7 are sewn to the sole in a corresponding fashion to the heel part portion and, on account of the fact that they are merely loosely assembled in proper register with the sole manually by the operator as the sewing proceeds, no 35 difficulty is experienced in allowing the horn properly to penetrate right to the toe of the sandal as sewing is carried out therearound since, at this stage, one side of the upper will still be unattached. When securing has been carried 40 out right round the sole and the point at which sewing was started is again reached, the two ends of the thread may be tied together in suitable manner to prevent the stitches running loose.

The nature and scope of the invention having 45 been indicated, and a machine embodying the features of the invention having been specifically described, what is claimed is:—

1. The method of securing the flanged sole to the heel and forepart of the upper of a Sahara sandal which comprises forming a series of lac- 50 ing holes in adjacent edges of the sole and upper parts, placing the sole and an upper part in proper relative position and presenting them with their edges abutting to a chain stitch McKay sewing machine with a perforation in the needle path, and moving the work after each reciproca- 55 tion of the needle to bring the perforations in the upper part and sole alternately into the needle path to form an ornamental seam con- 60 necting the parts and sole consisting of a series of chain stitches, the enchain loops of which

extend across the abutting edges on the outside of the sandal.

2. The method of securing the flanged sole to the heel and forepart of the upper of a Sahara sandal which comprises placing the sole and an 5 upper part in proper relative position and presenting them with their edges abutting to a chain stitch McKay sewing machine, and moving the work after each reciprocation of the needle to cause the needle to pass alternately through 10 the upper part and sole to form an ornamental seam connecting the upper part and sole consisting of a series of chain stitches, the enchain loops of which extend across the abutting edges 15 on the outside of the sandal.

3. The method of securing the flanged sole to the heel and toe part of the upper of a Sahara sandal which comprises placing the sole and an upper part in proper relative position and presenting them with their edges abutting to a chain 20 stitch McKay sewing machine, and moving the work after each reciprocation of the needle to cause the needle to pass alternately through the upper part and sole and to pass alternately through the sole and outside of the sole edge along 25 the space between the toe and heel portions of the upper to form an ornamental seam consisting of a series of chain stitches, the enchain loops of which extend across the abutting edges 30 of the sole and upper parts on the outside of the sandal and over the edge of the sole along the space between the toe and heel portions of the upper.

4. A machine for use in securing the flanged sole to the heel and forepart of the upper of a 35 Sahara sandal which comprises stitch forming devices including a work supporting horn, a straight hook needle, a thread finger, means for moving the thread finger into contact with the needle loop between the needle and the work 40 during each stitch forming cycle, and means for supporting the thread finger to permit it to yield upon contact with the needle.

5. The method of securing the flanged sole to the heel and forepart of the upper of a Sahara 45 sandal which comprises placing the sole and an upper part in proper relative position and presenting them with their edges abutting to a chain stitch McKay sewing machine, stopping the machine after each stitch forming cycle with the 50 needle slightly below its highest position and with the loop of thread on the needle in a flattened condition, and moving the work after each reciprocation of the needle to cause the needle to pass alternately through the upper part and 55 sole to form an ornamental seam connecting the upper part and sole consisting of a series of chain stitches, the enchain loops of which extend across the abutting edges on the outside of the sandal.

CHARLES MARTIN BAGSHAW.
